CUTTING DEVICE

Edward F. Arnold, New York, N. Y.

Application May 27, 1949, Serial No. 95,610

3 Claims. (Cl. 30—2)

1

This invention relates to a cutting device, and more particularly to a device for cutting open cartons, boxes, containers used for packing purposes.

In the past there have been provided several types of carton openers which usually provide a holder for a blade, a handle, and a guide member. In many instances the blades in the holder may be fixed loosely to said holder with the result that there is a tendency upon continued use of the cutter for the blade to become loose and to cut the carton unevenly. Furthermore, when passing such a cutter over the edge of a carton there may be a tendency for the blade during the cutting of the carton to extend into the interior of the container and damage the contents of said container.

In view of the above and other disadvantages, it is an object of my invention to provide a carton opener in which the blade or cutting portion of said opener extends from the handle of the opener and is disposed at such an angle with respect to the marginal edge of the carton being opened that there is no danger of the contents of the carton being damaged.

It is another object of the present invention to provide a carton opening device of simple, compact and economical construction in which the cutting member forms a permanent and integral part of said device.

Still another object of the present invention is to provide a cutting device for paper cartons and the like in which the cutting member of the device is so disposed that it cuts into the carton at a line below the marginal edge of the carton, said cutting being done at an upwardly inclined angle so as to avoid cutting into the contents of the carton.

Other objects and advantages will become apparent from the following description taken in conjunction with the accompanying drawings, in which:

Fig. 1 is a perspective, partially fragmental, view of a preferred embodiment of the invention;

Fig. 2 is an end sectional view showing the embodiment as applied to a carton so as to cut the marginal edge of said carton;

Fig. 3 is a plan view, partially broken away, of Fig. 1;

Fig. 4 is a plan view showing details of a portion of the embodiment shown in Figs. 1, 2, and 3; and

Fig. 5 is a modification of Fig. 4.

Referring to the drawings in which like numerals refer to like parts throughout, there is

2

provided a guide member 10 consisting of two faces 11 and 12, respectively, disposed at right angles to each other so as to form an integral unit, which is adapted to act as a guide when used against a marginal edge 13 of a carton or box 14, as shown in Fig. 2 of the drawing. The faces of said guide as shown are smooth and slide very easily over said edge of the carton. Face 12 is provided with a handle member 15 which is attached in any suitable manner, such as by the use of screw members 16 extending from said face into the handle. It will be noted that the handle is provided with a slot or groove 17 adapted to accommodate the base 18 of cutting blade 19 which is of substantially triangular shape and provided with beveled cutting edges, as shown. Said slot is disposed at an inclined angle with respect to the longitudinal axis of said handle while face 12 is provided with an inclined slot 20 in alignment with groove 17 in said handle 15 so as to accommodate a portion of cutting blade 19, extending from the handle 15.

It will be noted that said groove 17 in the handle is of sufficient depth and length to rigidly retain the base section 18 of said blade while the slot or groove 20 in said face 12 is of sufficient length to accommodate the base of the blade and prevent slippage of the same from the face.

A modified form of blade 21, as shown in Fig. 3, is provided having a pair of spaced, terminal-depending portions 22 and 23 enabling it to fit snugly into a groove 24 of corresponding shape in handle 25.

In the modification shown in Fig. 5 it will be noted that the base of blade 21' is provided with a central depending section 26 adapted to fit into a groove 27 of corresponding shape in handle 28. Said blade 21' has a flat, sharp cutting edge portion 29 to permit the blade at said edge to extend parallel with and adjacent the inner wall 30 of carton 14.

When the device is to be used it is placed so that one of the faces, namely 11, is flush against the top of carton 14, as shown in Fig. 2, whereupon the face and handle portions 12 and 15 slide against the vertical wall and blade 19 is forced through that upper marginal area of the carton so that the pointed edge 31 of the blade pierces the vertical wall of the carton and thereby facilitates the cutting operation, as shown, without cutting into any of the contents in the container 14. The angle of said blade 19 as it extends from face 12 into the carton 14 is such that the apical portion does not protrude very far from the inner

wall 30 of said carton but instead extends toward the inner horizontal wall 32 of carton 14.

Furthermore, because of the relative position of the cutting edge of the blade in the holder there is produced a diagonal cutting in the vertical wall of the carton adjacent the cover of said carton. In this manner there is produced a clean but inclined cut in the carton. Furthermore, because of the inclined position of the blade, as shown in Fig. 2, there is little likelihood of the 10 blade cutting the user of the device.

The device made according to my invention can be of any suitable material, such as metal, wood, or plastic, and may be of unitary construction in which the blade forms a permanent part of the device. The edges of said blade, while beveled, can be easily sharpened by grinding or filing.

While a preferred embodiment of the invention has been disclosed it is understood that changes as to form, material, and arrangement of parts may be made without departing from the spirit and scope of the invention as claimed.

I claim:

1. A cutting device of the class described for opening corrugated cartons and the like at a line parallel with the corner to be cut, comprising a member having a pair of faces joined at right angles relatively of each other for sliding over the edge of the carton to be cut, a handle member fixed to and extending perpendicularly from one of said faces, and a cutting edge of substantially triangular shape having a base fixed to the handle and its other edges extending angularly from the handle through one of said faces upwardly toward the other face but short of touching said face.

2. A cutting device for opening cartons and the like adjacent their folded marginal edge, comprising a slide member having a pair of faces disposed at right angles to each other and adapted to slide along the corner of the carton to be cut, handle means extending perpendicularly from

one of said faces forming part of one of said faces for operating the slide member against the carton in a horizontal or vertical direction, and a triangular shaped blade having one of its sides fixed in the means and extending at an incline therefrom through one of the faces toward the other face adapted to cut through the carton at a sharp incline toward but below the marginal edge without damaging the contents of the carton, said blade being reciprocably movable along the carton edge to cut the same in either direction without cutting or damaging the contents thereof.

3. A device for reciprocably cutting a carton and the like at the corner thereof in an upwardly inclined angle, comprising a right angled member having extending sides slidable along the corner of the carton, one of said sides having an inclined groove therein, a handle fixed to one of the sides extending perpendicularly therefrom, and a triangular shaped cutting member extending through said inclined groove, said cutting member having an apical carton piercing portion and downwardly inclined cutting edges extending from the apical portion to permit cutting of the carton at a line parallel with the corner but below and at an incline relatively thereto to prevent contact with the contents of the carton, said handle having an inclined seating groove for one of the sides of the triangular shaped member, said cutting member being movable in either direction along the corner of the carton.

EDWARD F. ARNOLD.
